FURNACE AND METHOD OF OPERATING THE SAME

Original application filed July 21, 1925, Serial No. 44,957. Divided and this application filed June 5, 1926.
Serial No. 113,856.

Our present invention relates to furnaces, particularly furnaces for use with solid fuel and in connection with a steam boiler, and methods for operating such furnaces, and 5 will be best understood from the following description and the annexed drawings of an illustrative embodiment of our invention and of an apparatus by which our method may be carried out. This is a division of 10 our application Serial No. 44,957, filed July 21, 1925.

The drawing is a side view, more or less diagrammatic, of the boiler and furnace, showing the exterior combustion air supply 15 system.

Like reference characters indicate like parts throughout the drawings.

In the illustrative embodiment, the steam boiler which we have chosen for purposes of 20 illustration, is provided with water tubes 10, uptake headers 11, downtake headers 12 and a steam and water drum 13, all connected in the usual manner. Baffles 14 and 15 direct the gases entering at the bottom of the first 25 pass adjacent the uptake headers, back and forth across the water tubes to the gas exit 16.

The combustion chamber is formed so as to have a narrow mid-section. In the lower 30 part of the combustion chamber is a chain grate stoker 17 which receives its fuel from a hopper in the usual manner, and carries it to the right, the ashes being deposited in the usual ash hopper through the opening 19.

At the front of the stoker 17 are a pair of 35 curved arches 20 and 21, the latter projecting over the forward part of the grate to form a combustion arch therefor. Similarly, at the rear of the chain grate stoker 17 is an arch 22 and an arch 23, the latter also forming a combustion arch or roof extending well forwardly over the rear end of the stoker. The inner ends of the arches 21 and 23 are curved 40 so as to provide a narrow passage 24 into which the gases from the stoker are directed 45 by the arches 21 and 23.

The passageway 24 merges into a combustion chamber 25 which preferably is provided with upwardly and outwardly diverging walls, the chamber 25 preferably having a flat 50 roof 26 suspended over it with a gas outlet

27 at one side of the roof 26 leading into the first pass of the boiler.

At each side of the widened part of the narrow passage 24 are auxiliary combustion air inlets arranged to direct the air crosswise 55 of the passage. A series of nozzles 28 extend across the furnace side by side, the rear end of each of the nozzles communicating with an air duct 29 on each side of the passageway 24.

The combustion air supply for the furnace is shown, in which an air heater 34 of any of the well-known types heats the combustion air entering the air heater through the duct 35. The heated air then flows through the duct 36 to and through the fan 37 and a feed water heater or economizer 45 into a duct 38 which communicates with spaces along the stoker 17 and between the runs thereof to supply the usual combustion air flowing through 70 the fuel on the grate. From the fan 37 leads also a duct 39 which communicates with the ends of each of the ducts 29 from which the air flows through the nozzles 28 into the narrow passage 24. Dampers in the several 75 ducts are provided so that the amount of air delivered to any part of the furnace can be controlled.

With the arrangement described, the furnace is preferably operated as follows:

Air is supplied through the duct 38 at pressures insufficient to lift the heavier particles of the fuel from the bed, but in sufficient quantities to burn the solid fuel on the grate. The amount supplied, however, is insufficient to complete the combustion of the gases rising from the grate. Such incompletely burned gases, together with the finer particles of fuel, are directed by the arches 21 and 23 to the narrow passage 24, from which they expand through the narrow passage 24 into the combustion chamber 25, mingling with additional combustion air from the nozzles 28, this auxiliary or additional combustion air being supplied in sufficient quantity to complete the combustion of the gases and fine particles of fuel. By bringing all of these gases and fine particles into a comparatively narrow space, the additional air is thoroughly mixed therewith so that as these 100

gases expand into the combustion chamber 25, the gases and fine particles are substantially completely burned before passing into the gas outlet 27. It will be noted that, by our arrangement, any possible stratification of the gases and air rising from the grate, which stratification occurs in furnaces as heretofore made, is entirely avoided by directing all of the gases and air passing through the grate into the narrow throat. By forming the combustion chamber 25 as shown, the gases therein are given a turbulence which completes the mixing of the air and gases, which mixing is aided by the provision of the gas outlet at one side of the combustion chamber.

We have found from experience with this type of furnace and with the method of operation as described above, that the amount of air supplied can be regulated close to the theoretical amount of air required for the complete combustion of the fuel, without any appreciable amount of excess air. In practically all cases, the quantity of air supplied through the grate is larger than that supplied through the nozzles 28. Preferably we arrange the dampers in the ducts 38' leading to the spaces beneath the fuel bed so that little or no air passes through the fuel at the front and middle portions of the grate and so that a somewhat larger quantity of air flows through the rear end of the grate, the quantities of air that do pass through the grate being such as to be used up largely in the burning of the solid fuel on the grate. Consequently, the gases which enter the narrow throat 24 are partly unburned combustible gases.

In the narrow throat 24, the unburned gases and the auxiliary combustion air are brought together in a small space and the subsequent expansion into the upper combustion chamber intimately mixes the two and the combustion is thereby substantially completed. The passing of the gases through the narrow passage 24 between the larger spaces below and above the passage acts like a Venturi tube, so that there is substantially no increase of draft resistance, the pressure, at least under some conditions, being lower in the passage 24 than it is in the upper and the lower parts of the combustion chamber.

By arranging the roof arch 23 in the manner shown, we have found that a large part of the relatively fine particles of burning fuel that may be carried up from the rear end of the fuel bed by the combustion air supplied beneath it, is thrown forwardly and down on the incoming fuel and thereby aiding the igniting of the fresh fuel, instead of being carried up into the upper combustion chamber, the slope of this arch being arranged to produce this effect.

We preferably operate the furnace so that the pressure at the narrow passage 24 is neg-

ative and thereby avoid too high a heat at this point, which would tend to destroy the arches 21 and 23.

The air ducts 29 cool the walls surrounding the narrow passage through which the burning gases pass and also serve to support the arches 21 and 23. These arches preferably are suspended in a well-known manner on metallic members on which the tile are suspended, these metallic members, in turn, being supported on hangers connected to the iron-work of the ducts. We have found that the cooling effect of the ducts 29 is such that arches can be maintained over the fuel bed which would otherwise be impossible, and the heat carried away from the walls of the air ducts 29 by the air is recovered and returned to the furnace.

As is well known, it is advantageous to supply the combustion air in a heated condition, but particularly where this heated air is supplied through a grate, it is necessary, in order not to destroy the grate, to keep the temperature of the heated combustion air below certain limits. On the other hand, in order to complete the combustion of gases, as, for instance, in the upper part of the furnace 25, it is desirable to have the combustion air heated to as high a degree as possible. In the arrangement which we have illustrated, the temperature of the air supplied beneath the grate 17 is lower than the temperature of the air supplied through the nozzles 28, because this additional air supplied through the nozzles 28 receives additional heat as it flows through the ducts 29.

Preferably, we heat the air directly from the flue gases as they emerge from the boiler and this produces a temperature too high to be used directly under the grate. In such cases, the temperature of this part of the air may be reduced by abstracting some of the heat from this portion of the combustion air by passing this heated air over the feed water heater or an economizer 45, the feed water being delivered to the drum 13 through the pipe 46. With this arrangement, the air from the heater 34 may be heated to any desired degree, and it will be delivered at substantially this high temperature to the nozzles 28. But the portion of this heated air which is delivered beneath the grate will be at a considerably lower temperature by reason of the abstraction of some of its heat by the economizer or feed water heater. It will be understood that the temperature of the air supplied beneath the grate may be reduced to any desired extent by regulating the flow of the water past the heating surface of the water heater or economizer 45 and thereby varying the amount of heat abstracted from the air, such regulation being effected, in the form illustrated, by by-passing more or less of the feed water through the pipe 47.

The arrangement illustrated by which the

combustion air is heated directly by the boiler waste gases without reducing the temperature of the gases by an economizer or the like, and then transferring some of the heat to the boiler feed water before supplying the air to the fuel is advantageous irrespective of the particular way in which the air is used. In such an arrangement, the heating surfaces of the economizers are contacted only with clean and relatively dry air instead of with the dust-laden products of combustion, so that the tubes or the like usually found in economizers are kept free from dust and possible corrosion from the mixture of the sulphurous gases and the like with moisture on the tubes.

It will be understood that the arrangements which we have shown are merely illustrative and that the embodiment of our invention may be widely varied. It will also be understood that certain features of our invention may be used with or without other features, as desired.

We claim:

1. The method of operating a boiler furnace having a fuel grate in its lower part, which comprises heating all of the combustion air to a high temperature, dividing the heated air into two streams, reducing the temperature of one stream by transferring some of its heat to the boiler feed water, supplying the air of reduced temperature beneath the grate and supplying the heated air from the other stream to the gases rising from the fuel on the grate at a point above the grate.

2. The method of operating a boiler furnace having a fuel grate in its lower part, which comprises heating all of the combustion air to a high temperature, dividing the heated air into two streams, reducing the temperature of one stream by transferring some of its heat to the boiler feed water, supplying the air of reduced temperature beneath the grate, causing the gases rising from the grate to flow together into a restricted space above the grate, supplying the heated air from the other stream to the gases as they pass through the restricted space and then permitting the mingled air and gases to expand into a larger combustion chamber to complete the combustion of the gases.

3. A steam boiler, a furnace to supply heated gases to the boiler, an air heater heated by the waste gases from the boiler, an economizer connected to the boiler, a duct to lead some of the heated air from the air heater to one part of the furnace, and ducts to lead the remainder of the air to the economizer and from the economizer to another part of the furnace.

4. A steam boiler, a furnace therefor having a fuel grate therein, an air heater heated by the waste gases from the boiler, an economizer connected to the boiler, a duct to lead some of the heated air from the air heater to the furnace at a point above the grate there-

in, and ducts to lead the remainder of the air from the air heater over the economizer to the furnace at a point beneath the grate therein.

5. A steam boiler, a furnace to supply heated gases to the boiler, an air heater heated by the waste gases from the boiler, an economizer connected to the boiler, a duct to lead some of the heated air from the air heater to one part of the furnace, ducts to lead the remainder of the air to the economizer and from the economizer to another part of the furnace, and means whereby the cooling effect of the economizer on the air passing therethrough may be varied.

6. A steam boiler, a furnace therefor having a fuel grate therein, an air heater heated by the waste gases from the boiler, an economizer connected to the boiler, a duct to lead some of the heated air from the air heater to the furnace at a point above the grate therein, ducts to lead the remainder of the air from the air heater over the economizer to the furnace at a point beneath the grate therein, and means whereby the cooling effect of the economizer on the air passing therethrough may be varied.

7. In combination, a steam boiler, a furnace therefor having a fuel grate therein, an air heater heated by the waste gases from the boiler, an economizer connected to the boiler, a duct to lead some of the heated air from the air heater to the furnace at a point above the grate therein, ducts to lead the remainder of the air from the air heater over the economizer and to discharge it at a plurality of points beneath the grate, and means to regulate the discharge of the air at said points.

8. The method of operating a furnace which comprises supplying a fuel to a combustion chamber, heating air, directing part of said air into said chamber, extracting some of the heat from the remainder of said air, and directing said remainder to the place at which said fuel is supplied to the chamber.

9. The method of operating a furnace which comprises supplying a fuel to a combustion chamber, heating air by the gases from said chamber, directing part of said air into said chamber, extracting some of the heat from the remainder of said air, and directing said remainder to the place at which said fuel is supplied to the chamber.

10. The method of operating a furnace which comprises supplying fuel to a grate in a combustion chamber, heating air, directing part of said air into said chamber above said grate, extracting some of the heat from the remainder of said air, and directing said remainder beneath said grate.

11. The method of operating a boiler furnace having fuel burning mechanism therein which comprises heating all of the combustion air to a high temperature, dividing the heated air into two streams, reducing the

temperature of one stream by transferring some of its heat to the boiler feed water, supplying the air of reduced temperature to said mechanism, and supplying the heated air from the other stream to the gases coming from said mechanism.

12. The method of operating a boiler furnace having fuel burning mechanism which comprises heating all of the combustion air to a high temperature, dividing the heated air into two streams, reducing the temperature of one stream by transferring some of its heat to the boiler feed water, supplying the air of reduced temperature to said mechanism, causing the gases coming from said mechanism to flow together into a restricted space, supplying the heated air from the other stream to the gases as they pass through the restricted space, and then permitting the mingled air and gases to expand into a larger combustion chamber to complete combustion of the gases.

13. The method of operating a boiler furnace having fuel burning mechanism which comprises heating all of the combustion air to a high temperature, dividing the heated air into two streams, reducing the temperature of one stream by transferring some of its heat to the boiler feed water, supplying the air of reduced temperature to said mechanism, causing the gases coming from said mechanism to flow together into a restricted space, and supplying the heated air from the other stream to the gases as they pass through the restricted space.

14. The method of operating a boiler furnace having fuel burning mechanism therein which comprises heating all of the combustion air to a high temperature, dividing the heated air into two streams, reducing the temperature of one stream, supplying the air of reduced temperature to said mechanism, and supplying the heated air from the other stream to the gases coming from said mechanism.

15. The method of operating a boiler furnace having fuel burning mechanism which comprises heating all of the combustion air to a high temperature, dividing the heated air into two streams, reducing the temperature of one stream, supplying air of reduced temperature to said mechanism, causing the gases coming from said mechanism to flow together into a restricted space, supplying the heated air from the other stream to the gases as they pass through the restricted space, and then permitting the mingled air and gases to expand into a larger combustion chamber to complete combustion of the gases.
